A CORPORATION OF DELAWARE

TRACK-SHIFTING APPARATUS

Application filed May 23, 1929. Serial No. 365,319.

This invention relates to track shifting machines, and has reference more particularly to machines for this purpose employed in open mining and other extensive excavating operations. With machines of this class the track is raised from the road bed and shifted laterally in a step-by-step movement, as the car carrying the shifting mechanism is run from one section of track to another.

Heretofore, machines used for this purpose have been provided with a tiltable thrust boom for raising the track and car upon a pedestal, and lateral movement of the track has generally been produced by shifting the position of the boom with reference to the car, which is held clamped to the tracks. The boom is operated mechanically and is allowed angular movement by mounting it in a sleeve which is pivotally supported. Transverse motion is allowed by mounting the boom upon a carriage that may be moved from one side of the car to the other. The lowering and raising of the boom is accomplished by means of a gear engaging a rack on the boom.

Track shifting machines of the type described have always been attended with certain disadvantages which it is the object of this invention to overcome. Among the disadvantages may be mentioned the following: excessive strains upon certain parts of the operating mechanism, such as the teeth on the boom rack, which results in frequent breakage and repairs; excessive shocks due to jerky operation of the boom mechanism, resulting in short life to the machine and increased cost of operation; lack of accurate alignment in the shifted track, due to difficulty of close control of the boom mechanism.

In order to cure these defects applicant proposes generically to employ compressed air or hydraulic pressure apparatus instead of mechanically operated mechanism, as there are certain definite advantages in the use of compressed air, or a fluid, over purely mechanical means to accomplish track lifting. For example, a fluid cushioning effect is secured, which is impossible by mechanical means alone. Another advantage lies in the fact that there are no teeth on the boom which can be snapped off due to sudden over-

stress. A further advantage is the more flexible and easily controlled application of power to the operating mechanism, which greatly facilitates accurate operation.

We are aware that pneumatic and hydraulic jacks have heretofore been used in connection with track lifting, and ballasting machines where the object is merely to lift the track vertically, but, so far as we are aware, no one has heretofore attempted to solve the problem of track shifting by the use of fluid-operated mechanism for this purpose.

An object of this invention is to provide a track shifting machine that operates without excessive shocks and strains upon the operating mechanism.

A further object of this invention is to provide a track shifting machine in which the power is flexibly connected and applied to the operating mechanism.

A further object is to provide a device of this character wherein the power is gradually applied, and the operating mechanism accurately controlled.

A still further object of our invention is to provide a track shifting machine which is simple, durable, efficient and economical in operation.

A further object is to provide in a device of this kind an efficient and easily operated mechanism to firmly clamp the car to the rails and to release said car from the rails.

More specifically, it is our object to provide a track shifting machine comprising a self-propelled car adapted to travel on the track to be shifted, said car being clamped to the rails and provided with a fluid pressure boom arranged to lift and laterally shift said car and track.

With these and other objects in view, which may be incident to my improvements, the invention consists in the parts and combinations to be hereinafter set forth and claimed, with the understanding that the several necessary elements comprising our invention may be varied in construction, proportion, and arrangement, without departing from the spirit and scope of the appended claims.

In order to make our invention more clearly understood, we have shown in the accom-

panying drawings means for carrying the same into practical effect, without limiting the improvements in their useful application to the particular constructions, which, for the purpose of explanation, have been made the subject of illustration.

In the drawings:

Figure 1 is a plan view of our improved track lifting machine.

10 Figure 2 is a side elevation of the same.

Figure 3 is a transverse section along the line 3—3 of Figure 1.

15 Figures 4 and 5 are longitudinal vertical sections of one of the clamp mechanisms in clamped and open positions, respectively.

Figure 6 is a side elevation of the same.

Figure 7 is a plan view of the pipe layout showing connections from pressure tank to operating cylinders.

20 Figures 8, 9, 10 and 11 are horizontal sectional views of the fluid control valves in various operating positions.

Figure 12 is a vertical section of a fluid control valve.

25 Figure 13 is a vertical longitudinal section of the thrust boom cylinder and associated mechanism.

Figure 14 is a diagrammatic section showing the relative positions of the several principal elements during the operation of shifting a track.

30 Figure 15 is a plan view of the pipe layout showing connections from the tank to the operating cylinders for a liquid pressure system.

35 Referring by numerals to the drawing, wherein the same elements are designated by like symbols throughout, 1 designates a steel frame flat car, adapted to travel upon standard or narrow gauge tracks 2, and upon which are mounted all the necessary machinery to laterally shift said tracks.

40 Securely bolted to car 1 is an internal combustion engine or other prime mover 3, having secured to its crank shaft a driving sprocket 4 connected by chain 5 to a driven sprocket 6, which is in turn connected through a clutch 7 to a counter-shaft 8. On the other end of shaft 8 is a driving sprocket 9 connected by a chain 10 to a driven sprocket 11, which is fixed on the main shaft of a multi-cylinder air compressor 12 provided with the customary overload relief valve 12a. Pipe 45 13 connects the compressor to a pressure tank 14, from which a pipe 15 leads to control valves 16, 17 and 18. Pipe 19 is connected with the exhaust outlet of each of the valves and serves as an exhaust manifold. This 50 pipe may exhaust directly into the atmosphere or into the atmosphere through a suitable exhaust-modifying device. Flexible pipes 20 and 21 connect valves 17 and 18 with main cylinder 22, and pipes 23 and 24 connect

55 valve 16 with the four auxiliary cylinders 25. (See Figure 7.)

When the track shifting machine is in operation, prime mover 3 is in constant motion, and when it is desired to secure air pressure for the operation of main cylinder 22 and auxiliary cylinders 25, clutch 7, through its operating lever 7a, is caused to engage shaft 8 to sprocket 6 and power is thus transmitted from prime mover 3 to compressor 12, 75 which furnishes the desired air pressure to tank 14 and the operating cylinders 22 and 25.

80 While the fluid pressure system has been described with air as a working fluid, we wish it to be clearly understood that liquids may be advantageously employed. Such a system employing liquid as a working fluid is disclosed in Figure 15 where a liquid pump 100, of any suitable design, has its low pressure or intake connected with a sump or tank 14' by means of the pipe line or other coupling 13'. Liquid from the tank 14', which is under substantially atmospheric pressure is forced from the pump through pipe 15' to the valves 16', 17' and 18'. Pipe 19' is connected with the exhaust outlet of each of the valves and the tank 14' so that the exhaust fluids are returned thereto. As in the case of the pneumatically operated mechanism, suitable pipes 20' and 21' connect valves 17' and 18' with the lifting cylinder 22, while pipes 23' and 24' connect valve 16' with the four auxiliary cylinders 25. For the purpose of providing pressure relief 95 means between the high pressure side of the pump and the sump a suitable by-pass 101 is connected to the line 15' adjacent the pump discharge end and to the sump.

100 The pump 100 is driven in a manner similar to that employed for the air compressor. Upon the driven shaft 102 of the pump is mounted a sprocket similar to the sprocket 11, previously described. By means of the sprocket chains and couplings disclosed in connection with Figures 1 and 2, the sprocket secured to the pump shaft may be rotated so as to actuate the pump.

105 Slidably keyed to one end of the main crank shaft of prime mover 3 is a fly wheel 26, having a smooth face 27 held in frictional contact with driven wheel 28 by a lever 29 pivoted near its center to car frame 1, and engaging at one end with collar 30, integral with fly wheel 26, and at its other end attached to operating lever 31. As will be seen from Figure 1, operation of lever 31 causes fly wheel 26 to be brought into and out of frictional engagement with driven wheel 28, which is slidably keyed to counter-shaft 32, along which it is moved by operating lever 33 through a system of links engaging collar 34 on wheel 28. It is obvious 115 that the movement of wheel 28 across the face of fly wheel 27 causes changes of speed 120

125 130 135

in wheel 28 and will also reverse the direction of its rotation when it is shifted past the center of wheel 27.

Shaft 32 at its free end carries a crown gear 35, which meshes with a similar gear 36 fixed to a counter shaft 37, on which are slidably keyed a plurality of clutch collars 37 and 38, which are moved in unison along shaft 37 by a yoke 39 attached to an operating lever 40. As will be seen in Figures 1 and 2, clutch collars 37 and 38 are adapted to alternately engage similar collars 41 and 42, fixed respectively to sprockets 43 and 44 upon shift of yoke 37 by lever 40. Of course, when the yoke is in neutral position, there will be no engagement between any of the clutch collars. When collar 37 is engaged with collar 42, (as in Figure 1), power is transmitted from prime mover 3 to sprocket 44, and from thence through chains 45 and 46 to screw shafts 47. As will be seen in Figures 1 and 3, screw shafts 47 are journaled at their ends in the frame of car 1, and are engaged intermediate their ends by threaded sleeves 48, integral with standards 49, which are slidably mounted on cross beams 50 rigidly fastened to frame of car 1.

This invention further contemplates the substitution of the coupling clutches hereinbefore described by friction clutches. In either event the clutch actuating mechanism may be either manually or mechanically operated, such as by associating fluid pressure operated means with the actuating mechanism.

It is obvious from the foregoing that the motion imparted to screw shafts 47 will result in a movement of standards 49 from one side of car 1 to the other, depending upon the direction of rotation which may be regulated by friction drive 27-28, as explained above.

One of the standards 49 is provided at its upper end with an integral arcuate rack 51, which meshes with a pinion 52, fixed to a shaft 53, mounted in a boss 54 on main cylinder 22, and provided at its free end with an operating wheel 54. By turning wheel 54, pinion 52 is caused to travel over rack 51 and rotate cylinder 22 about its trunnions 55, which are journaled in the upper parts of standards 49.

When collar 38 is engaged with collar 41, power is transmitted from prime mover 3 to sprocket 43, and thence through chain 56 and sprocket 57 to one pair of wheels of car 1, which serve to propel the car along tracks 2.

Mounted in cylinder 22 is a close-fitting air-tight and liquid-tight piston 58, to which is attached a piston rod 59, which passes through a stuffing box 60 in the lower end of cylinder 22, and has pivotally secured to its free end a shoe 61 with corrugated face 62. When valves 17 and 18 are turned to the positions indicated in Figures 11 and 13, compressed air from tank 14 flows through pipes

15 and 21 to the lower part of cylinder 22, raising the piston 58 to the top of the cylinder, as shown. The air above the piston escapes through pipes 20 and 19 and valve 63 into the outside air.

If valves 17 and 18 are now turned as shown in Figure 10, the flow of air to and from cylinder 22 is cut off and piston 22 will remain in the position shown in Figure 13. If valves 17 and 18 are now turned as shown in Figure 9, air will enter the upper part of cylinder 22, forcing piston 58, rod 59 and shoe 60 downward until shoe 60 engages with the ground between the ties of track 2, as shown in Figure 14. If valves 17 and 18 are still left in the position shown in Figure 9, piston 58 will continue to descend in cylinder 22, and then reaction of shoe 62 on the ground will raise car 1 therefrom. The travel of piston 58 can be arrested at any time and in any position desired and held in such position for any desired length of time by turning valves 17 and 18 to the position shown in Figure 8 and cutting off the supply and escape of air to and from cylinder 22.

It is obvious that when the liquid pressure system of Figure 15 is employed, upon the valves 17' and 18' being positioned as described in connection with the similar valves 17 and 18 used with the compressed air system, the piston 58 within the lifting cylinder will be similarly controlled. In this instance, however, instead of the fluid being exhausted into the atmosphere, it is returned through the exhaust line 19' to the sump 14' and recycled.

Each auxiliary cylinder 25 contains an air-tight piston 64, to which is attached a piston rod 65, which passes through a stuffing box in the lower part of cylinder 25 and is attached by a yoke 66 to a pair of pivotally mounted tong clamps 67 and 68. Links 69 and 70 connect clamps 67 and 68 to lifting bar 71, which surrounds piston rods 65 and is slidably mounted in the frame of car 1.

Lifting bar 71 is provided at its upper end with a heavy annular flange 72, which engages with frame of car 1 when in lowermost position, as in Figure 4. When, however, piston rod 65 is retracted until tong clamps 67 and 68 are wide open, (as in Figure 5), further retraction of piston rod 65 results in raising bar 71, as shown in dotted lines in Figure 5, so that clamps 67 and 68 completely clear tracks 2 when car 1 is traveling thereon.

The operation of clamps 67 and 68 is controlled by valve 16, which admits compressed air from tank 14 through pipes 15 and 23 and 24 to cylinders 25. When valve 16 is turned to the position shown in Figure 11, air enters the tops of cylinders 25, depressing piston 64 and rods 65, and causing clamps 67 and 68 to embrace the balls of rail 2, the air in the lower part of cylinders 25 escaping through pipe 19. If valve 16 is now turned

115

120

125

130

to the position of Figure 10, all air is cut off from entrance and exit from cylinders 25, causing piston rods 65 to remain in lowermost position, as shown in Figure 4.

If valve 16 is now turned as shown in Figure 9, air enters the lower ends of cylinders 25 through pipes 15 and 24, raising piston rods 65 to position shown in Figure 5, and when valve 16 is turned as shown in Figure 8, this position is held. When piston 65 and clamps 67 and 68 are in position shown in Figure 4, and air is admitted to main cylinder 22, depressing piston 59 and raising car 1, it is manifest that the frame of car 1 engages the flanges 72, and through bars 71 and clamps 67 and 68, also raises track without causing any stress on piston rods 65.

When the liquid pressure system of Figure 15 is used, positioning of the valve 16' in a manner similar to that described in connection with the valve 16 will cause the track clamps to be controlled as described above.

As will be appreciated by the foregoing description, our invention contemplates broadly a machine for raising or shifting the position of tracks, either standard gauge or narrow gauge, by means of compressed air or hydraulic cylinder. The machine consists mainly of a power unit, (prime mover), air compressor or hydraulic pump with a receiver or liquid tank, compressed air or hydraulic cylinder, and such accessories as are necessary to accomplish the results stated above.

In our improved track shifting machine the car, platform, or mounting is attached to the rails by track clamps. These track clamps are operated by means of a control valve in such a way that on moving the valve lever in one direction, the track clamps are lowered into place and clamped to the rails, and when the lever is moved in the opposite direction, the track clamps are released from the rails and raised upward for the purpose of avoiding obstructions when traveling. The unique feature of our track clamps is that by means of one lever the clamps may be lowered and attached to the rail, and the same lever furnishes the means of detaching the clamps from the rail and raising them up. Another feature of these clamps is that the greater the weight to be lifted the greater the clamping power exerted, also no strain of lifting is transferred to the lever mechanism used for raising or lowering.

The power unit (prime mover) is connected to the air compressor or hydraulic pump either directly or by chain, gears, belts, clutches or a combination of these so that the air compressor or hydraulic pump may be stopped even though the power unit be left running. This air compressor or hydraulic pump furnishes the pressure which is to operate the piston within the cylinder, 60 to raise or shift the track.

In the case of compressed air, the air is compressed by the usual method and delivered under pressure to the air receiver or reservoir. From this reservoir a pipe line or lines leads to a system of operating valves 70 operated separately or together in such a way that the air or liquid may be delivered to either top or bottom of the cylinder, raising or lowering the piston and piston rod therein and by this means raising or lowering the track upon a supporting shoe. These same valves may be used also to close the openings leading to or from the top or bottom of the cylinder so that the track, after being raised, may be held in place, or by further manipulation of these valves the top or bottom openings in the cylinder may be 80 opened to the atmosphere or liquid tank, releasing the compressed air or liquid in the cylinder.

In the case of a hydraulic system the hydraulic pump obtains its liquid from a liquid tank and through the pump discharge delivers the liquid through a pipe or pipes to the operating valves. These valves are then 90 manipulated in the manner described for raising, holding, or shifting the track, and the only difference between the compressed air and a hydraulic system is that where with compressed air the exhaust ports are opened 95 to the atmosphere, in a hydraulic system the liquid is returned to the liquid tank by means of a pipe or pipes and is not exhausted.

In order to facilitate the raising of either one side of the track at a time, raising both sides together, or raising and shifting the position of the track, the cylinder is mounted upon the car in a carriage, which is caused to slide at right angles to the track direction by means of ordinary worm type screws, 100 which in turn are operated by the prime mover through shaft gears, belts, chains, or clutches, or a combination of these, so that the direction of sliding of this carriage may be reversed to place the cylinder in any position within the limits of the worm type screws.

The cylinder may be tilted at any angle by means of a hand wheel and gear attached to the cylinder by a pin, upon which the hand wheel and gear are free to revolve together. The gear engages in teeth cut in the top of the carriage, thus causing a tilting of the cylinder by revolving the hand wheel in either direction, since the cylinder is attached to the carriage by means of pins which are free to revolve in bearings.

The car, platform, or mounting to which this equipment is attached is to be propelled in either direction by means of a transmission of power through shafts, gears, belts, chains, or clutches or a combination of these.

The car, platform, or mounting, in case of the use of wheels, may be equipped with hand or foot controlled brakes, which may be ac- 130

tuated either manually or by means of a fluid under pressure.

A typical cycle of operations would be as follows: The car, platform, or mounting is 5 propelled to the point where the track is to be raised or shifted by the means described above. The track clamps are lowered and clamped to the rails. The cylinder carriage is then slid into proper position as described 10 above and the cylinder given the correct angle of tilt for the raising or shifting by means of the hand wheel. By means of the operating valves, air or liquid, as the case may be, is forced into the top of the cylinder, 15 causing the plunger and shoe to descend, and this in turn raises the track together with the car, platform, or mounting. By the correct angle of cylinder tilt and placing of the cylinder carriage the track may be raised 20 on either side, both sides together, or may be shifted to either side through the combined efforts of the cylinder and the forces of gravity. After the track has been lowered or shifted, the machine may be moved to a 25 new position. Figure 14 shows the relative positions assumed by the principal elements of our machine in shifting a track from right to left.

It is apparent from the above description 30 that our pneumatic or hydraulic valves afford a means of carefully controlling the movement and operation of our machine so as to avoid a sudden jerk, shock or jar such as are commonly encountered in mechanically operated machines of this kind. This 35 not only enables the operator to more accurately align his shifted track, but adds greatly to the life of the machines and avoids breakage due to sudden overstress of vital parts.

The cushioning effect of fluid pressure operation greatly facilitates these beneficial results.

While we have shown and described the 45 preferred embodiment of our invention, we wish it to be understood that we do not confine ourselves to the precise details of construction herein set forth, by way of illustration, as it is apparent that many changes 50 and variations may be made therein by those skilled in the art, without departing from the spirit of the invention, or exceeding the scope of the appended claims.

We claim:

- 55 1. In a track shifting machine, a power source and a fluid pressure actuated track raising and shifting mechanism.
2. In a track shifting machine, a power source and angularly adjustable, a fluid pressure actuated means for raising and shifting a track.
- 60 3. In a track shifting machine, a car having a power source mounted thereon, said car adapted to be secured to the rails to be shifted, and a fluid pressure actuated means

for raising and shifting said car and track.

4. In a track shifting machine, the combination of a car adapted to be secured to the rails to be shifted, and an angularly adjustable fluid pressure actuated means for raising and shifting said car and track. 70

5. In a track shifting machine, the combination of a car adapted to be secured to the rails to be shifted, and a fluid pressure actuated thrust boom adapted to raise and shift said car and track. 75

6. In a track shifting machine, the combination of a car adapted to be secured to the rails to be shifted, and an angularly adjustable fluid pressure actuated thrust boom adapted to raise and shift said car and track. 80

7. In a track shifting machine, a car adapted to travel on the tracks to be shifted, means for securing said car to said tracks, fluid pressure actuated means for operating said securing means, and means for lifting said car and track without exerting strain upon said operating means. 85

8. In a track shifting machine, a car adapted to travel on the tracks to be shifted, means for securing said car to said tracks, fluid pressure actuated means for applying said securing means to said tracks and for withdrawing same above said tracks. 90

9. In a track shifting machine, a railway car, means to clamp same to the rails upon which it rests, a fluid pressure actuated thrust boom pivotally and slidably mounted on said car, and means to angularly adjust said boom. 95

10. In a track shifting machine, a railway car, fluid pressure actuated clamping means carried thereon adapted to firmly secure said car to the track upon which it rests and fluid pressure actuated means for raising and shifting said car and track. 100

11. In a track shifting machine, a railway car, hooks carried by said car adapted to engage the rails upon which said car rests, fluid pressure actuated means to raise and lower said hooks and to apply and withdraw them from said rails. 110

12. In a track shifting machine, a railway car, hooks carried by said car adapted to engage the rails upon which said car rests, fluid pressure actuated means to raise and lower said hooks and to apply and withdraw them from said rails, and means to raise said car and track without applying stress to the hook actuating means. 115

13. In a track shifting machine, a railway car, fluid pressure actuated means on said car adapted to clamp same to the rails upon which it rests, a carriage transversely adjustable on said car, a fluid pressure actuated thrust boom pivotally mounted on said carriage, and means to adjust the angular position of said boom on said carriage. 120

14. In a track shifting machine, a railway car, fluid pressure actuated means on said 125

car adapted to clamp same to the rails upon which it rests, a carriage transversely adjustable on said car, a fluid pressure actuated thrust boom pivotally mounted on said carriage, and a prime mover for propelling said car and actuating said clamp means, carriage and boom.

15. In a track shifting machine, a railway car, fluid pressure actuated means on said car adapted to clamp same to the rails upon which it rests, a carriage transversely adjustable on said car, a fluid pressure actuated thrust boom pivotally mounted on said carriage, a source of power, and power transmitting mechanism to operate said car, clamp means, carriage and boom.

16. In a track shifting machine, a railway car, fluid pressure actuated means on said car adapted to clamp same to the rails upon which it rests, a carriage transversely adjustable on said car, a fluid pressure actuated thrust boom pivotally mounted on said carriage, a shoe pivotally attached to said boom, and mechanism to angularly move and adjust said boom.

17. In a track shifting machine, a railway car, toggle hook clamps for securing said car to said rails, fluid pressure actuated means for applying and withdrawing said clamps from said rails, and means to lift said car and rails without applying stress to said clamp actuating means.

18. In a track shifting machine, a railway car, adapted to travel on the rails to be shifted, fluid pressure actuated means to clamp said car to said rails, and fluid pressure operated means to lift and shift said car and rails.

19. In a track shifting machine, a railway car, adapted to travel on the rails to be shifted, hydraulic means to clamp said car to said rails and hydraulic means to lift and shift said car and rails.

20. In a track shifting machine, a power source, and angularly adjustable, a fluid pressure actuated means for raising a track and holding the same in raised position.

21. In a track shifting machine a car having a power source mounted thereon, said car adapted to be secured to the rails to be shifted, a fluid pressure actuated means for raising said car and track, controlling means for said fluid pressure actuated means so that the car and track may be held in a raised position and lowered therefrom when desired.

22. A track shifting machine comprising a car having a power source mounted thereon, said car adapted to be secured to the rails to be shifted, a fluid pressure actuated means for raising and shifting said car and track, controlling means for said fluid pressure actuated means so that the car and track may be held in a raised and shifted position and may be lowered when desired.

23. A device for clamping a railway car to

a track comprising a cylinder mounted on the body of said car, a piston therein adapted to be actuated by fluid pressure, a piston rod therefor, said piston rod being of a length sufficient to extend through the body of said car, a tubular bar surrounding said piston rod and also extending through the body of said car, a pair of tong clamps pivotally connected to the free end of said piston rod, and a link connecting each tong clamp with said bar.

24. A device for clamping a railway car to a track comprising a cylinder mounted upon the body of the car, a piston therein adapted to be actuated by fluid pressure, a piston rod and a tubular bar surrounding the same extending through the car body, said bar being slidably mounted in the car body and provided with a flange at one end adapted to rest upon the car body when the piston is at one extreme position, the other end of said rod being connected by a plurality of links to a pair of tong clamps pivotally mounted on the free end of said piston rod.

25. In combination with a track shifting machine comprising a railway car having fluid pressure actuated track raising and shifting mechanism mounted thereon, fluid pressure actuated track clamps for securing the car to a track on which it runs, each of said clamps comprising a cylinder, a piston and piston rod therein, a pair of tong clamps mounted upon the free end of each of said piston rods, and means for opening and closing said clamps upon the movement of said pistons.

26. In combination with a track shifting machine comprising a railway car having fluid pressure actuated track raising and shifting mechanism mounted thereon, fluid pressure actuated track clamps for securing the car to a track on which it runs, each of said clamps comprising a cylinder mounted upon the body of the car, a piston therein, a piston rod therefor and a tubular bar surrounding the same extending through the car body, said bar being slidably mounted in the car body and provided with a flange at one end adapted to rest upon the body when said piston is at one extreme position, the other end of said rod being connected by a plurality of links to a pair of tong clamps pivotally mounted upon a yoke secured to the free end of said piston rod, said yoke adapted to bear against the end of said bar when the piston is moved away from the car body so as to raise said bar with said clamps.

27. A track raising and shifting machine comprising a car adapted to be clamped to the rails on which it runs, cross beams positioned transversely of said car, a standard slidably mounted on each cross beam, a fluid pressure actuated thrust boom mounted between said standards, means for adjusting the position of said standards and means for

angularly adjusting the position of said thrust boom.

28. A track shifting machine comprising a car adapted to be clamped to the rails on which it runs, cross beams positioned transversely of said car, a standard slidably mounted on each cross beam, a cylinder pivotally mounted between said standard, said cylinder being provided with a piston and piston rod therefor, a pedestal mounted upon the free end of said piston rod, means upon the car for moving said cylinder transversely thereof, said piston being actuated by fluid pressure to raise and shift the car and track.

15 29. A track shifting machine comprising a car adapted to be clamped to the rails on which it runs, a power source mounted upon said car, cross beams positioned transversely of the car, a standard slidably mounted on each cross beam, a cylinder pivotally mounted between said standards, said cylinder being provided with a piston and piston rod therefor, a pedestal mounted upon the free end of said piston rod, each of said standards provided with a threaded sleeve adapted to engage a screw shaft rotatably mounted on the car, and means for coupling said screw shafts to the power source so as to adjust the position of the cylinder, said piston being actuated by fluid pressure to raise and shift the car and track.

30 30. A track shifting machine comprising a car adapted to be clamped to the track on which it runs, cross beams positioned transversely of said car, a standard slidably mounted on each of said cross beams, a cylinder pivotally mounted between said standards, means upon one of said standards for adjusting the angular position of said cylinder, each of said standards being provided with a threaded sleeve adapted to engage a screw shaft rotatably mounted on said car, and means for connecting said screw shafts to said power source so as to rotate the same and move said cylinder transversely of the car, said piston being actuated by fluid pressure to raise and shift the car and track.

35 31. A track shifting machine comprising a car, a power source and a lifting cylinder provided with a piston and piston rod therefor, said cylinder being pivotally mounted between standards slidably transversely of said car, each of said standards being provided with a threaded sleeve adapted to engage a screw shaft journalled in said car, said piston rod being provided with a pedestal for lifting and shifting a track, a plurality of cylinders provided with pistons and piston rods, the latter having clamp mechanism mounted thereon for securing the car to the track on which it runs, means for coupling said power source with said screw shafts so as to rotate the same and adjust the position of said cylinder, and means for coupling said

power source with a fluid pressure generator mounted on said car.

32. A track shifting machine comprising a car adapted to be clamped to the rails on which it runs, a power source, a fluid pressure generator, and fluid pressure actuated track raising and shifting mechanism mounted on said car, said track raising and shifting mechanism being slidable transversely of the car, means for coupling said power source to said track raising and shifting mechanism so as to position the same, means for coupling said power source with said fluid pressure generator so as to actuate the same, and means for coupling said power source with an axle of said car so as to propel the car along the track.

15 33. In a track shifting machine, a power source, air compressor and compressed air actuated track raising and shifting mechanism.

34. In a track shifting machine, a car having a power source and air compressor mounted thereon, said car adapted to be secured to the rails to be shifted, and means for conducting the air compressed by said compressor to a track raising and shifting mechanism so as to raise and shift the car and track.

20 35. In a track shifting machine a car having a power source and an air compressor mounted thereon, said car adapted to be secured to the rails to be shifted, an angularly adjustable compressed air actuated means for raising and shifting said car and track, and means for conducting air compressed by said compressor to said raising and shifting mechanism.

25 36. A track raising and shifting machine comprising a car adapted to be clamped to the rails on which it runs, a power source, air compressor, a tank and a lifting cylinder mounted thereon, said cylinder provided with a piston and piston rod, the latter provided with a pedestal for raising and shifting said car and track, means for coupling said power source to said compressor, the air compressed thereby being stored in said tank, a three-way valve associated with each end of said lifting cylinder for controlling the admission and exhaustion of air therein, an air inlet line from said tank and an exhaust line connected to each valve.

30 37. A track shifting machine comprising a car adapted to be clamped to the track upon which it runs, a plurality of clamp actuating cylinders, a main lifting cylinder having a piston and piston rod provided with a pedestal, a power source, an air compressor and a tank mounted on said car, means for coupling said power source with said compressor so as to actuate the same, the air compressed thereby being stored in said tank, a three-way valve associated with each end of the lifting cylinder, a four-way valve asso-

ciated with the ends of the clamp actuating cylinders, an air inlet line from said tank and an exhaust line connected to each of the valves, said valves adapted to control the admission and exhaustion of air in the cylinders.

38. In a track shifting machine, a power source, a liquid reservoir, a pump and a hydraulically actuated track raising and shifting mechanism.

39. In a track shifting machine a car adapted to be clamped to the track on which it runs, a power source, a pump, a liquid reservoir and hydraulically actuated mechanism for raising and shifting said track and car.

40. In a track shifting machine a car adapted to be clamped to the track on which it runs, a power source, a pump, a liquid reservoir and angularly adjustable hydraulically actuated mechanism for raising and shifting said car and track.

41. In a track shifting machine a car adapted to be clamped to the track on which it runs, a power source, a pump, a liquid reservoir and a hydraulically actuated thrust boom adapted to raise and shift said car and track.

42. In a track shifting machine a car adapted to be clamped to the track on which it runs, a power source, a pump, a liquid reservoir and an angularly adjustable hydraulically actuated thrust boom adapted to raise and shift said car and track.

43. A track shifting machine comprising a power source, a liquid reservoir and pump mounted on said car, means for securing the car to the track on which it runs, hydraulically actuated mechanism for operating said securing means, and means for lifting said car and track without exerting a strain upon said operating mechanism.

44. In a track shifting machine, a railway car, a power source, a liquid reservoir and pump mounted thereon, hydraulically actuated clamping means carried upon said car adapted to secure the car to the track upon which it runs, and hydraulically actuated means for raising and shifting said car and track.

45. In a track shifting machine comprising a car, a power source, a liquid reservoir, a pump and a hydraulically operated track raising and shifting mechanism mounted upon said car, means for connecting said power source to said pump, said pump adapted to force liquid through said raising and shifting mechanism so as to actuate the same, means for returning the liquid thereto from said reservoir, and means for clamping the car to the track.

46. In a track shifting machine comprising a car adapted to be clamped to the track on which it runs, a power source, a liquid reservoir, a pump and hydraulically operated

mechanism for raising and shifting the car and track, means for coupling said pump to said power source, said pump adapted to force the liquid through said raising and shifting mechanism so as to actuate the same, means for returning the liquid therefrom to said reservoir, said pump positioned on the high pressure side of the system, and means for controlling the fluid admission and exhaustion in said raising and shifting mechanism.

47. In a track shifting machine comprising a car, hydraulically operated track clamps for securing the car to the track on which it runs, hydraulically operated mechanism for raising and shifting the car and track, a power source, a reservoir and a pump mounted on said car, means for coupling the power source to said pump, said pump adapted to draw liquid from said reservoir and force the same through said pump to the clamping and the raising and shifting mechanism to actuate the same, means for returning the liquid from said clamping and raising and shifting mechanism to said reservoir, and means for controlling the admission and exhaustion of said liquid in the clamping and the raising and shifting mechanism.

In testimony whereof we affix our signatures.

GROVER J. HOLT.
WILFRED LONGEVIN.
